UNITED STATES PATENT OFFICE.

FRANCIS C. HOBBS, OF NEW YORK, N. Y., ASSIGNOR TO BRUNSWICK-BALKE-COLLENDER COMPANY, A CORPORATION OF NEW YORK.

BILLIARD-CHALK HOLDER.

1,121,560.

Specification of Letters Patent. Patented Dec. 15, 1914.

Application filed May 1, 1913. Serial No. 764,788.

To all whom it may concern:

Be it known that I, FRANCIS C. HOBBS, a citizen of the United States, residing at New York city, county of New York, and State 5 of New York, have invented certain new and useful Improvements in Billiard-Chalk Holders, fully described and represented in the following specification and the accompanying drawings, forming a part of the 10 same.

This invention relates to certain improvements in holders for billiard chalk, and particularly to hanging holders suspended by cords or chains.

15 It is the object of the present invention to produce an improved holder which shall hold the block of chalk firmly so that the cue may be properly chalked therewith, and which, at the same time, shall be made so 20 as to prevent the removal of the chalk from the holder until the block is substantially used up.

It is a further object of the invention to produce such a construction in which, as the 25 chalk is used and the block or cake of chalk decreases in thickness, the holder may be accommodated to such decreased dimensions of the chalk and the chalk held firmly therein.

30 It is a further object of the invention to provide a holder in which, after the chalk has been hollowed out by use, the edges of the block or cake of chalk may be trimmed down without removal of the block from the 35 holder.

One embodiment of the invention is illustrated in the accompanying drawings, in which—

Figure 1 is a perspective view of the improved holder having therein a block of chalk; Fig. 2 is a vertical section of the holder showing the construction employed for preventing the removal of the chalk; Fig. 3 is a section taken on the line 3—3 of 45 Fig. 2, and Fig. 4 is a side view of one member of the chalk-holder, showing a method of forming the tongues employed for preventing the accidental removal of such part of the holder from the other part.

50 Referring now to these drawings, the improved holder comprises a chalk holding member which, in the particular construction illustrated, is in the form of a casing or cage 1 of suitable material, as thin metal, or open at one end and provided at its other

end with an aperture 2, around which are holding or supporting flanges 3 on which the chalk block 4 rests. The aperture 2 permits access to the chalk of the cue-tip to which the chalk is to be applied, and the 60 aperture 2 is of a size, as illustrated in dotted lines in Fig. 3, sufficient to expose nearly the whole end face of the chalk block, enough of the block being left unexposed to permit it to seat on the flanges 3. The cage 65 1 is preferably provided in one or more of its sides with elongated apertures or slots 5 formed near the lower edge of the cage. These apertures permit the insertion of a knife or similar tool for the purpose of trimming off the edges of the chalk block as the chalk is hollowed out centrally through use and it becomes desirable to level the face of the chalk block.

Coöperating with the cage 1 is a second 75 member 6 formed to fit in the cage and inclose the top end of the chalk block located therein. The construction of this member may be somewhat varied, but preferably this member is in the form of a casing of 80 thin metal which acts as a follower having portions as 7 adapted to contact with the top of the chalk block and acting to hold the block firmly in position in the cage. This member is readily movable in one direction in the cage so that it may be kept in contact with the chalk block as the latter decreases in thickness, but is held normally from movement in the other direction so that the accidental bodily removal of the 90 chalk by players may be prevented. The construction by which this result is effected may be somewhat varied. In the preferred construction, and as illustrated, the follower 85 6 will be provided with means coöperating 95 with means located in the cage 1, and out of the way of easy access. As illustrated, the cage is provided on two opposite sides with a series of lateral ridges 8 having sharp edges, these edges, as shown in Fig. 2, projecting downwardly, forming, in effect, teeth. On the follower 6 are located tongues 9 of spring or resilient material, conveniently formed by cutting or stamping the metal follower as shown in Fig. 4 and bending the upper edges of the tongues outwardly so that they will project beyond the sides of the follower, the tongues being also forced outwardly by the insertion of the chalk block. These spring tongues permit 100 105 110

the follower to be pressed downwardly in the cage, but spring into engagement with the teeth 8 and effectually prevent upward movement and withdrawal of the chalk 5 from the cage. The holder is supported above the billiard table in any suitable manner, as by a cord 10, knotted as at 11, in a flanged portion 12 projecting from the top of the follower. When the chalk block has 10 been nearly used up, it may be broken and removed from the holder and the tongues sprung back into their normal positions and permit the follower to be removed from the cage, a fresh piece of chalk inserted therein, and the follower replaced.

By the invention illustrated, an improved chalk holder is provided which is durable, cheap to make, which effectually prevents the bodily removal of the chalk from the 20 holder without considerable difficulty, and which at the same time permits the free use of the chalk and ready access to the chalk block for trimming the same.

While the invention has been shown in 25 what is considered its best form, it will be understood that it is not to be restricted to the exact construction shown and described, but that variations may be made in the same without departing from the scope of the invention.

What is claimed is:—

1. A chalk-holder comprising a chalk-holding member and a member coöperating therewith to prevent the bodily removal of chalk from the holder, said members being 35 freely movable relatively to each other in one direction while the block of chalk is in the holder, but restrained from such movement in the opposite direction.

40 2. A chalk-holder comprising a chalk-holding cage and a follower fitting therein over the chalk, said follower being freely movable in the cage in one direction while the block of chalk is in the holder but held 45 against movement in the opposite direction.

3. A billiard chalk-holder comprising a chalk-holding cage provided on two opposite sides with projections and a follower fitting in the cage over the chalk and provided 50 with spring tongues adapted to slip past the projections when moved in one direction but to engage therewith when moved in the opposite direction, whereby the follower may be moved in the cage to follow the chalk 55 but restrained from movement in the opposite direction.

4. A billiard chalk-holder comprising a chalk-holding cage and a follower fitting therein and over the sides of the chalk, said follower being provided on its sides with 60 means engaging with the cage for preventing the withdrawal of the follower from the cage.

5. A billiard chalk-holder comprising a chalk-holding cage provided in its bottom 65 with an aperture through which the chalk may be reached by a cue-tip and having on two opposite sides projections, and also provided on one or more of its sides with an aperture through which the chalk may be 70 reached to be trimmed, and a follower fitting in the cage and over the chalk and provided with tongues arranged to engage with the projections and prevent the withdrawal of the follower from the cage. 75

6. A chalk-holder comprising a chalk-holding shell, projections on one side of the shell, a follower fitting in the shell over the chalk, and a spring tongue on the follower 80 engaging the projections on the cage to prevent the withdrawal of the follower from the cage in one direction.

7. A chalk-holder comprising a holding casing having projections on one of its inner walls, a cap fitting in the casing extending down over the sides of the chalk, a block of chalk in the cap, and a spring tongue formed in the side of the cap and forced into engagement with the projections on the casing and preventing the movement of the 90 follower relatively to the casing in one direction.

8. A billiard chalk-holder comprising a holding casing open at the top and provided with an apertured chalk-holding seat at the 95 bottom, a cap fitting in the casing and extending down over the sides of a chalk-block positioned in the cap, downwardly extending teeth on one of the inner side walls of the casing, and an upwardly-extending 100 spring tongue on the follower cap in engagement with the teeth when the cap is inserted in the casing whereby the cap is prevented from upward withdrawal from the casing. 105

In testimony whereof, I have hereunto set my hand, in the presence of two subscribing witnesses.

FRANCIS C. HOBBS.
